Henry Breitmeyer,
By his Attorney
John A. Donegan

UNITED STATES PATENT OFFICE.

HENRY BREHMEYER, OF PRINCETON, NEW JERSEY.

SPARK-PLUG.

1,258,180.

Specification of Letters Patent.

Patented Mar. 5, 1918.

Application filed August 18, 1916. Serial No. 115,133.

To all whom it may concern:

Be it known that I, HENRY BREHMEYER, a citizen of the United States, residing at Princeton, county of Mercer, and State of New Jersey, have invented certain new and useful Improvements in Spark-Plugs, of which the following is a specification.

This invention relates to improvements in spark plugs, and has for its general object to provide a construction which will render those parts of the plug which are exposed directly to the action of the gases in exploding, easily accessible when occasion requires that the said parts be inspected or cleaned. And a further object is to provide means for preventing short circuiting through the plug. And to these ends the invention resides in adapting the insulator and the casing therefor to coöperate so as to leave exposed a generous portion of the inner end of the insulator, in providing a scraper for the exposed inner end portion of the insulator and in adapting such scraper to be operated by the explosion of the gases when these are ignited in the firing chamber.

Other objects will appear and be better understood from that embodiment of my invention of which the following is a specification, reference being had to the accompanying drawings forming part hereof and in which:

Figure 1, is a detail showing the casing in vertical longitudinal section and the insulator partly in section and partly in side elevation.

Fig. 2, is a detail sectional plan taken through the exposed inner end portion of the insulator and showing the scraper.

In the drawings "a" indicates the plug, the casing 5 of which is formed of metal and has what will be subsequently termed its inner end portion 6 screw threaded, and its outer end portion somewhat enlarged and polygonal in contour as indicated by 7. The screw threaded portion 6, screws into the usual opening in the wall of an engine cylinder and the polygonal outer end portion 7 provides a surface onto which a wrench may be readily adjusted in the act of attaching the plug to or detaching it from the cylinder. The bore 8 of the sleeve extends from the inner end thereof to approximately the middle portion where it terminates in a counter-bored portion 9. The presence of the counter-bored portion 9 provides an interior shoulder 10, at the middle portion of

the sleeve. The insulator 11 extends through the sleeve and between its ends the said insulator has a cylindrical enlargement 12 which corresponds in diameter approximately to that of the counter-bored portion 9, in which it is disposed and arranged between the shoulder 10 and the lock nut 13 which is screwed into the counter-bored portion 9. Gaskets 14 are interposed between the adjacent surfaces of the enlargement 12, the lock nut 13 and the shoulder 10, and the lock nut is adjusted so as to coöperate with the shoulder 10 to exert pressure on the intervening parts so that leakage around the enlargement 12 will be prevented. The bore 15 of the lock nut is enlarged with respect to the bore 8 of the sleeve and the outer end portion 16 of the insulator which passes through the bore 15 of the lock nut corresponds approximately in diameter to the bore thereof. Thus it will be seen that the portion 16 is sufficiently thick to give the stability required of an insulator in a device of this kind. The insulator 11 has a longitudinal bore 17 in which is disposed the electrode 18. The outer end portion of the electrode 18 extends beyond the corresponding end portion of the insulator and is screw threaded as indicated at 19. A binding nut 20 is screwed onto the portion 19 and operates to secure the terminal of the electrical conductor or wire to the projecting end portion of the electrode 18.

The inner end of the electrode 18 is provided with a substantially spherical shaped head 21 which is disposed in the counter-bored inner end portion 22 of the insulator. And the said counter-bored portion 22 is so proportioned with respect to the size of the head that the same is practically housed within the counter-bore. With this construction it is obvious that the electrode presents but a minimum of surface to be operated upon when it is found necessary to remove soot or carbon therefrom. The head 21 moreover is adapted to coöperate with the binding nut 20 to tighten the electrode in the insulator and prevent leakage through the bore thereof. The inner end portion 23 of the insulator is relatively thin as compared with the outer end portion 16 and fits nicely within the bore 8 of the casing 5. A considerable length of the inner end portion 23 is exposed and extends beyond the inner end of the casing 5. This construction permits of inspecting or cleaning

when occasion requires and without requiring removal from the casing that portion of the insulator which is exposed to the flame of the gases in exploding. A finger or electrode 24 is secured to the inner end of casing 5 and has its free end portion bent or otherwise suitably disposed so as to coöperate with the head 21 of the electrode 20 to provide an intervening space which constitutes the usual spark gap.

It will now be noted that by reason of the length of the inner portion 23 and the exposed extension thereof the said spark gap will, when the plug is connected to the usual type of cylinder be disposed well within the explosion chamber with the result that when the mass of explosive mixture is compressed in the firing chamber the spark will ignite such mass at the central portion thereof.

Manifestly the exposed extension of the inner portion 23 of the insulator and the finger or electrode 24 will present surfaces onto which carbon will readily deposit. Therefore and in order to prevent a rapid accumulation of carbon on these parts a scraper 25 in the form of a ring arranged on the exposed extension of the inner portion 23 of the insulator and a recess 26 is formed in the scraper which receives the finger or electrode 24. The scraper is made relatively narrow so that it will have an appreciable amount of sliding movement on the exposed extension on the inner portion 23 and on the finger or electrode 24, and a stop 27 arranged in a groove 28 near the end of the inner portion 23 is provided for preventing displacement of the scraper from the insulator. When the spark plug is connected to a cylinder and arranged in an upright position the scraper 25 is supported by the stop 27 so that when a charge of combustible mixture is exploded at a point below the scraper, the explosion will cause the scraper to ascend until it strikes against the inner end of casing 5. After the explosion of the mixture the scraper will descend until it strikes the stop 27. Thus it will

be seen that the scraper reciprocates on the insulator and electrode 24 and by this action operates to prevent the relatively rapid formation of a film or coating of carbon between the electrodes and the casing 5 with the result that short circuiting of the current through the plug will be prevented. It is obvious that the scraper 25 may be modified so as not to engage electrode 24 and thereby operate on the exposed extension only.

What is claimed as new is:

1. In a spark plug the combination of a casing, an insulator disposed therein and having one end portion exposed and extending beyond the inner end of the casing, an electrode secured to the casing and a scraper slidingly mounted on the extended end portion of the insulator and on the electrode.

2. A spark plug comprising an open ended casing having an interior shoulder and communicating bored and counter-bored portions, an insulator disposed in the casing and having its inner end portion snugly fitting within the bored end portion of the casing and extending beyond the end thereof, said insulator being provided with a longitudinal bore the inner end of which terminates in a counter-bore and further having an intermediately disposed enlargement arranged in the counter-bored portion of the casing and supported by the shoulder, an electrode arranged in the bore of the insulator and having in its inner end a head disposed in the counterbore of the insulator, a second electrode connected to the casing and disposed in operative relation to the head of the first named electrode, a lock nut surrounding the insulator and disposed in the casing and a scraper slidingly mounted on the extending inner end portion of the insulator and on the second named electrode.

In testimony whereof, I have signed my name to this specification, this 12th day of August 1916.

HENRY BREHMEYER.
